W. J. Mottur
Attorney

UNITED STATES PATENT OFFICE.

JOSEPH MOTTUR, OF BROOKLYN, NEW YORK.

ELASTIC SELF-SUPPORTING HOSE.

Application filed June 19, 1926. Serial No. 117,054.

This invention relates to wearing apparel and more particularly to such articles of apparel as are constructed of knit fabric and in tubular form. The invention is herein 5 illustrated embodied in a hose, but it is within the purview of the invention to embody the salient features thereof in other articles of the general character above mentioned.

It is an object of the invention to provide 10 an article of the character mentioned which shall be self-sustaining or supporting.

With reference to the embodiment illustrated, it is an object of the invention to provide 15 a hose which shall be wholly self-supporting and which will afford the utmost of comfort and service to the wearer.

It is a further object of the invention to provide 20 a hose of the character mentioned wherein is embodied an elastic portion of suitable dimensions to produce a sufficient binding action to maintain the hose in the proper position, and yet which will not be a source of discomfort to the wearer thereof.

A further object resides in the construction 25 of the contractable top portion whereby the said contracting or gripping portions are constituted by alternate fibre and elastic walls whereby the gripping is effected largely by the tension placed upon the fabric portions.

30 A further object of the invention resides in the provision of an additional circular elastic band adjoining the top portion of the hose and secured to or made integral with the elastic portions above mentioned.

35 Further objects and important characteristics of the invention will appear from the following detailed description in connection with the accompanying drawing, wherein:

Fig. 1 is a view in side elevation showing 40 the invention in the manner in which it is applied.

Fig. 2 is an enlarged view in side elevation of the hose shown in Figure 1.

Fig. 3 is a sectional view taken on a horizontal line passing through the top of the 45 hose of Figures 1 and 2.

Fig. 4 is a developed plan view of the top portion of the hose showing the relationship of the alternate fabric and elastic portions.

50 Fig. 5 is a view in side elevation of a somewhat modified form of the invention, embodying the features of the other construction and having certain features in addition thereto.

55 Fig. 6 is a perspective view of the elastic

portions employed in the hose illustrated in Figure 5.

Referring now in detail to the drawings, the reference character 1 designates the body portion and 2, the foot portion of a hose 60 either of conventional or of any preferred form. The upper portion of this hose is formed or provided with openings in the side walls thereof, constituting thereby separate front and rear walls 4 and 3 respectively, the 65 said walls being formed in the usual manner as extensions of the body portion 1. These lateral openings are provided with elastic portions 5 which may either be formed therein by known processes of knitting or formed 70 separately and thereafter secured therein by stitching or in any other suitable manner. The location of these elastic portions and their relation to the fabric walls to which they are secured is quite clearly shown in 75 Figures 3 and 4. By referring to Figure 3 it will be seen that a hose of this character when in use will have the front and rear walls 4 and 3 thereof placed under an appreciable tension by the elastic inserts, whereby the entire top structure is adapted to firmly grip 80 the limb of the wearer. It will be noted that the gripping action is not confined to the elastic portion alone but is distributed substantially uniformly over the entire tubular 85 top structure. Thus the gripping portion is of very large area and consequently does not exert an uncomfortable pressure on any portion of the wearer's limb. This feature is regarded as of outstanding importance over 90 structures wherein the gripping action is confined to a relatively small area such for example as in the case of the ordinary stocking supporter or in hose having elastic bands of 95 small dimensions associated therewith.

The somewhat modified form of the invention shown in Figures 5 and 6 embodies the features of the form described above and in addition thereto embody a circular elastic band adjacent to the upper edge of the top of the hose and secured to or formed with the downwardly extending elastic inserts. In these figures the reference character 10 designates the body of the hose and numerals 11 and 12 designate the rear and front portions 100 respectively. The numeral 13 designates the elastic inserts corresponding to numbered portions 5 in the other figures, these inserts however are formed with or have secured thereto the circular elastic band 14. This 105

band is of the same diameter as the normal diameter of the hose top with the elastic inserts thereof in relaxed condition. The band 14 may be secured to the upper edges of the 5 fabric walls 11 and 12 or may be left entirely free therefrom. It is also contemplated that the band 14 may be secured to the upper edge of wall 12 and left entirely free of the upper edge of wall 11 or vice versa. In case the 10 band 14 is secured to the front wall 12 but left free of the rear wall 11, the rear portion of the band may be employed in the manner of a garter by pulling it upwardly from the upper edge of the hose, and in case both the 15 front and rear portions of the band are left free, they may both be moved upwardly to enhance the gripping effect. With the band secured to the top of the hose at both the front and rear portions thereof it will be seen 20 that the gripping effect will be greatest in the immediate vicinity of the band and that the gripping action is thus increased.

While the invention is herein shown as being embodied in a hose, it is to be understood 25 that the invention contemplates the embodiment thereof in other articles of this general character and that the present disclosure is merely illustrative of a single possible embodiment. For example the features 30 of the invention may be embodied in either the sleeves or legs of body garments, in gloves, wristlets and many different forms of bandages for medical purposes.

The application of the present invention is 35 specifically contemplated in connection with women's and children's hose as well as golf and other sport hose in addition to the conventional men's half hose herein shown.

The elastic portions may be formed of any 40 suitable material and by any suitable process but it is preferred that the same be of knit construction similar to that now employed in the manufacture of garters and other elastic wearing apparel. It has been found advantageous 45 to employ a knit elastic material of

relatively fine texture in order to avoid chafing and other discomfort.

Having now fully described my invention with relation to an illustrative embodiment thereof and pointed out the most advantageous manner of producing and using the same, what I claim as my invention and desire to protect by Letters Patent is as follows:

1. In an article of the class described, a hose having the usual body portion, a top having a section removed from the wall thereof and an elastic insert secured to said wall in lieu of the removed portion, a circular elastic band secured to said insert and having its lower edge loosely resting upon the top edge of the 60 hose.

2. In an article of the class described, a hose having the usual body portion, a top portion having sections removed from opposed portions of the wall thereof, constituting thereby, opposed openings and arcuate wall sections, an elastic insert in each said opening and connecting said wall sections and a wide friction-gripping elastic band loosely resting upon the upper edge of said 70 top portion and secured to said inserts.

3. As a new article of manufacture, a self-supporting men's half hose, comprising foot and body portions of conventional construction and design and a top portion formed in connection with said body portion, said top portion having substantially rectangular openings formed in the opposite side walls thereof, defining thereby, spaced, opposed arcuate front and rear walls, a substantially 80 rectangular elastic element disposed in each of said openings and secured to the said front and rear arcuate walls, the circumferential dimensions of the hose thus formed being substantially the same as those of the original 85 unaltered hose, and a circular elastic gripping band having an edge superimposed on the top of said arcuate walls and inserts and secured to the latter.

JOSEPH MOTTR.
